UNITED STATES PATENT OFFICE.

LOUIS J. GOTTO, OF GREEN BAY, WISCONSIN.

TRACK-MOTOR.

1,359,359.

Specification of Letters Patent. Patented Nov. 16, 1920.

Application filed March 29, 1920. Serial No. 369,540.

To all whom it may concern:

Be it known that I, LOUIS J. GOTTO, a citizen of the United States, and resident of Green Bay, in the county of Brown and State of Wisconsin, have invented certain new and useful Improvements in Track-Motors; and I do hereby declare that the following is a full, clear, and exact description thereof.

10 My invention relates broadly to new and useful improvements in power producing mechanisms, particularly to that type which are actuated by waste energy of other machines.

15 Specifically the invention pertains to motors for driving any type of machinery and the primary object is to provide a motor of this character which can be actuated by the passage of railway cars and similar vehicles over their track rails.

20 An additional object of the invention is to provide a series of simply constructed motors which can be mounted at the side of a railway rail so that they will be successively actuated by the flanges of the vehicle wheels which run on said rail.

25 With these general objects in view the invention consists in the novel features of construction, combination and arrangement of parts which will be hereinafter more particularly described and claimed and shown in the drawing, wherein:

30 Figure 1 represents an elevational view of a pair of rail fragments to each of which one of my improved motors is connected, one of said motors being shown in elevation and the other in section, and

35 Fig. 2 is a transverse sectional view taken on the plane of the line 2—2 of Fig. 1.

40 Since it is entirely immaterial how the energy generated by my invention is used, I have not illustrated any particular means for collecting and applying such energy. It will be obvious, however, that various types 45 of driven machinery, such as dynamos and pumps, can be operated through the use of the invention. Likewise many changes may be made in the different parts of the invention and in the manner of mounting the same without departing from the principles thereof or sacrificing any of the advantages.

50 Referring more particularly to the accompanying drawing, the reference character R denotes a railroad rail of standard design having a head 1, a base 2 and a connecting

web 3. Secured at intervals to one side of the rail is a plurality of my improved motors M, the same being connected by a horizontal shaft 4. This shaft may be of any desired length and extends mid-way between the head and base of the rail, one end being connected with any desired type of machine to be driven by the rotation thereof.

55 Each of the motors M includes a bracket 5 having an intermediate web engaging portion, a combined head engaging and guide portion in which a guide is formed, and a base engaging foot 7, the free end of the same having a hook like portion 8 disposed over the edge of the rail base 2. Bolts 9 extend through the web of the rail and the intermediate portion of the bracket 5 to securely clamp the latter in rigid position upon the rail.

60 The intermediate part of the bracket 5 has a pair of horizontally disposed spaced bearing arms 10 projecting therefrom in which the shaft 4 is rotatably mounted. A gear 11 is loosely disposed on the shaft 4 between the pair of bearing arms and is held against rotation in one direction with respect to the shaft by means of a ratchet 12 and pawl 13. The former is keyed to the shaft 4 and the latter is carried by the gear 11.

65 The guide 6 is adapted to slidably receive a block 14 in the form of a plunger head which normally is disposed so that its upper surface is substantially flush with the top of the rail head 1. A rack 15 depends from the plunger head and is disposed between the bearing arms 10 with its teeth in engagement with the teeth of the gear 11. A guide roller 16 journaled between the free ends of the bearing arms 10 engages the plane surface of the rack 15 and co-operates with the guide 6.

70 The lower end of the rack 15 is extended to form a plunger stem 17 which is vertically movable in a socket 18. This socket is carried by the bracket foot 7 and houses a spring 19 which normally exerts its tension to urge the stem and consequently the plunger head upwardly.

75 In the use of the invention, it is obvious that when the flange of a railroad car wheel engages the plunger head 14, the same is forced downwardly with a like movement of the rack and rotation of the gear 11. The gear being locked to the shaft 4 when ro-

tated in this direction by means of the pawl and ratchet, said shaft will be revolved in order to drive any suitable mechanism with which it may be connected. Upon the disengagement of the wheel flange from the plunger head, the latter is returned to normal position by the expansion of the spring 19. The gear 11 is rotated in a reverse direction by the upward movement of the rack, 10 but being loosely mounted on the shaft, said shaft is not turned. By having a plurality of the motors M disposed at intervals along the track, it is obvious that they will be successively engaged by the flanges of the 15 car wheels and practically continuous rotation imparted to the shaft 4.

I claim:

The combination with a track rail of a bracket carried by the rail, a shaft journaled in the bracket, a gear loosely mounted on 20 the shaft, a plunger including a rack engaged with the gear and adapted to be reciprocated by the vehicle movable over the rail, and means for locking the gear to the shaft when the plunger moves in one direction. 25

In testimony that I claim the foregoing I have hereunto set my hand at Green Bay, in the county of Brown and State of Wisconsin.

LOUIS J. GOTTO.
